SLICING MACHINE

George R. Wood, Montreal, Quebec, Canada, assignor to Toledo Scale Company, Toledo, Ohio, a corporation of New Jersey

Application September 15, 1941, Serial No. 410,927

1 Claim. (Cl. 146—102)

This invention relates to slicing machines, and particularly to slicing machines of the type in which the commodity to be sliced is carried in an inclined commodity tray which is adapted to be moved back and forth over the cutting edge of a revolving circular knife, the commodity being fed to the knife by gravity. Certain features of the invention, however, are applicable also to other types of slicing machines.

It is an object of the invention to provide a slicer having a simple and readily removable commodity tray and commodity tray bracket, the construction of the machine being such that, with the commodity tray and commodity tray bracket removed, the machine is especially adapted for de-rinding, de-crusting and otherwise trimming meats and other commodities.

Another object is the provision of a slicing machine having a commodity tray so mounted on a concealed carriage, traveling on concealed rails, as to be easily moved to and fro over a revolving knife edge.

Other objects and advantages will be apparent from the following description, in which reference is had to the accompanying drawings illustrating a preferred embodiment of the invention and wherein like reference numerals designate similar parts throughout the several views.

In the drawings:

Fig. I is a view in perspective showing a slicing machine embodying the invention.

Fig. II is a front elevational view showing principal parts of the slicing machine of the invention in vertical section, taken substantially through the axis of rotation of the revoluble circular knife plate.

Fig. III is a left-side elevational view of the slicing machine, parts being broken away and parts being shown in section.

Fig. IV is a right-side elevational view of the machine with the commodity tray removed and with parts shown in section substantially along the line IV—IV of Fig. II.

Fig. V is a front elevational view with parts broken away and parts shown in section, taken along the line V—V of Fig. IV.

Fig. VI is a fragmentary elevational view, taken from the position indicated by the line VI—VI of Fig. II, showing the lower end of a commodity tray supporting bracket.

Fig. VII is a fragmentary view showing the manner in which the commodity tray is adjustably secured to the commodity tray supporting bracket.

Fig. VIII is a fragmentary sectional view taken substantially along the line VIII—VIII of Fig. VII.

Fig. IX is a fragmentary sectional view taken substantially along the line IX—IX of Fig. II.

Fig. X is an enlarged sectional view showing an adjusting knob.

Fig. XI is a fragmentary view in section taken substantially along the line XI—XI of Fig. V.

Fig. XII is a fragmentary sectional view taken substantially along the line XII—XII of Fig. V.

Referring to the drawings in detail, the machine is supported upon three rubber feet 20 which are secured, by means of screws 21, in seats 22 formed in the lower side of a cast frame 23.

The cast frame 23 consists principally of a base portion 24, which supports the knife-driving mechanism and the commodity receiving tray, and a housing portion 25 extending fore and aft along the right side of the base portion and enclosing and supporting a stationary shaft 26 upon which a commodity tray carriage 27 is slidably mounted.

10 The carriage 27 (as illustrated in Figs. II, IV and V) is substantially T shaped, with annular bearing members 28 located at the termini of its horizontal arms and encircling the stationary shaft 26. The lower end of the vertical stem of the T shaped carriage 27 carries a guide roller 29 which is located between and rolls along horizontal rails 30 and 31 that are secured to and lie along the lower part of the housing portion 25.

15 The rail 31 lies beneath, and is spaced from, the vertical outer wall of the housing portion 25, so that a slot is left between the rail 31 and the lower edge of the outer wall of the housing portion, and a foot 32 of the vertical stem of the carriage 27 is turned outwardly through this slot 20 and terminates in an enlarged, machined pad 33.

20 A commodity tray supporting bracket 34, having a complementary machined seat 35, is secured by means of a knurled screw 36, to the foot of the carriage 27, the machined pad on the carriage and the machined seat on the bracket being firmly engaged and prevented from turning relative to each other about the axis of the knurled screw 36 by suitable rabbets.

25 To facilitate removal and replacement of the commodity tray bracket 34, a slot 37 is cut downwardly from the shank of the screw 36 so that when the screw is loosened and the machined pad and seat are disengaged the bracket may be lifted without entirely removing the screw.

30 The upper end of the bracket 34 is curved over the top of the housing portion 25 and provided with a trough-like seat within which the V shaped bottom of a commodity tray 38 is secured by means of screws 39 in a manner which will be specifically described hereinafter. A handle 40 is fixed to the commodity tray bracket 34 to facilitate manual fore-and-aft reciprocation of the commodity tray, the handle being so placed that the operator's thumb or fingers

are not liable to touch the knife when the handle is grasped.

Mounted upon the base portion 24 of the cast frame 23 is an electric motor 41 having a shaft 42 upon which is fixed a worm 43 that extends into a gear casing 44, also mounted upon the base portion 24, the gear casing being further secured to the motor.

The gear casing 44 is provided with a cylindrical opening 45, the axis of which extends upwardly and to the right at an angle of approximately 45 degrees from the horizontal, and removably mounted within the cylindrical opening 45 is a sleeve 46 within which is journaled, by means of antifriction bearings, a revoluble shaft 47 (see Fig. II). Fixed upon the left end of the revoluble shaft 47 is a worm wheel 48 which meshes with and is turned by the worm 43. The portion of the gear casing 44 surrounding the worm 43 and worm wheel 48 constitutes a reservoir for lubricating oil. The sleeve 46 is retained in place in the cylindrical opening 45 by means of a setscrew 49.

Fixed near the right end of the revoluble shaft 47 is a hub 50, to which a circular knife 51 is removably securely by means of screws 52. The knife edge thus is inclined from a vertical plane by about 45 degrees. The lower edge of the knife 51 extends into a depression 53 in the upper wall of the housing portion 25, and the wall of the housing portion extending forwardly from the depression 53 is formed into a flat ledge 54 lying perpendicular to the plane of the knife, the ledge being continued over the depression 53 and to the rear end of the housing portion by a flange 55 of a knife guard 56 which overlies the knife 51. In order that the ledge may be smooth from end to end, the flange of the knife guard 56 which overlies the depression 53 is inset into the upper housing surface as indicated in Fig. II. The knife guard 56 is removably held in place by pins 57 and clips 58.

The shaft 47 extends through the hub 50 and has a point turned on its end which supports the center portion of the knife guard 56 to prevent the guard from flexing inwardly under the weight of the commodity being sliced on the machine.

Located within the housing portion 25 of the cast frame 23 are a pair of aligned bosses 59 and 60 (Figs. IV and V) having aligned bores within which is slidably mounted a short, stiff rod 61; and secured, by means of a setscrew 62, to the rod 61 is a gauge plate frame 63. The gauge plate frame 63 is prevented from rocking about the axis of the rod 61 by means of a stub rod 64 which is secured to the frame by a setscrew 65 and one end of which is slidably received in a bore in a third boss 66 formed within the housing portion 25. Adjustably secured, by means of screws 67, to the upper part of the gauge plate frame 63 is a gauge plate bracket 68, upon which is removably mounted a gauge plate 69, the gauge plate 69 being removably fastened to the gauge plate bracket by means of screws 70 threaded into strips 70' which are welded to the gauge plate. The face of the gauge plate 69 is parallel to and closely adjacent the plane of the knife 51, and the edge of the gauge plate adjacent the edge of the knife is concavely curved to conform closely to the edge of the knife.

As the circular knife wears and thus becomes

smaller, the crank between the concavely curved edge of the gauge plate and the knife edge widens. When this occurs the position of the gauge plate may be adjusted to again locate its concavity curved edge in close proximity to the knife edge by loosening the screws 67 and moving the gauge plate bracket on the gauge plate frame. The means for making this adjustment are concealed in the housing portion 25 but are

10 accessible from below.

Fixed to the gauge plate frame 63 is a short rack 71, the teeth of which mesh with a pinion 72 fixed upon the inner end of a knob stem 73 which is rotatably mounted in a boss 74 formed

15 within the front end of the housing portion 25. Turning of the knob stem 73 is yieldably resisted by a pair of friction washers 75 clamped between the boss 74 and a castellated nut 76 threaded upon the knob stem 73 (see Fig. X).

20 The outer end of the knob stem 73 projects to the exterior of the housing portion 25 and is provided with a knob 77, by means of which the knob stem 73 and pinion 72 may be turned to shift the rack 71, and consequently the gauge

25 plate frame 63 and bracket 68, to adjust the face of the gauge plate 69 toward or away from the plane of the knife 51, and thus adjust the thickness of slices to be cut. A commodity lying against the gauge plate 69 may be pushed

30 into engagement with and over the knife edge which, when the knife is rotated rapidly, will cut a slice from the commodity, the thickness of the slice depending upon the distance that the face of the gauge plate lies below and to

35 the left of the plane of the knife edge.

The knob 77 is marked with a series of indicia 78 indicative of various thicknesses of slices, which indicia cooperate with an index 79 formed upon a washer 80 interposed between

40 the knob and the front wall of the housing portion 25. The washer 80 is held against rotation by means of a pin 81, which also serves as a stop engageable by a projection formed upon a lock washer 82 which is keyed to the knob stem

45 73. Engagement of the projection with the pin 81 prevents the gauge plate 69 from being adjusted into the path of movement of the commodity tray 38. A spring 83 presses the washers 80 and 82 into frictional engagement which,

50 assisted by the friction between the washers 75 clamped against the boss 74 by the castellated nut 76, prevents the knob stem 73 from turning accidentally, and thus holds the gauge plate 69 reliably in adjusted position.

55 With the commodity tray and commodity tray bracket removed from the commodity tray carriage, a commodity may be slid along the gauge plate 69 and the ledge 54 into engagement with the knife edge. It is very convenient to handle, in this way, bacon which is to be de-rinded, bread which is to be de-crusted, and other commodities which are to be trimmed or which are to be sliced and which cannot be conveniently handled in the commodity tray.

60 65 With the commodity tray bracket and commodity tray in place, the lower left end of the commodity tray moves closely over the face of the knife guard 56. For the best operation, it is important that the end of the commodity tray move as closely as possible across the knife edge. The knife guard 56, however, overlies the knife edge at the rear of the machine. Therefore, a portion of the end of the commodity tray has been cut back, as at 38', to permit it to pass the overlying

70 75 part of the knife guard at the termination

of the rearward movement of the tray (see Fig. I), and a portion of the knife guard at the lower rear edge of the knife has been cut away, as at 56', to permit the uncut back portion of the commodity tray end to move rearwardly far enough to move any commodity in the tray completely over the knife edge.

In order that the position of the commodity tray 38 may be adjusted to bring its end very close to the face of the knife guard 56, channel members 84 are welded or brazed to the commodity tray (as shown in Figs. VII and VIII) and the channel members are provided with elongated openings 85 through which the screws 39 extend, the screws being threaded into bars 86 which, when the screws are tightened, are clamped against the interior of the channel members 84.

The motor 41 and the gear casing 44 are surrounded by a cast enclosure 87 which is fastened to the base portion 24 of the cast frame 23 by suitable lugs and screws 88. The front wall of the enclosure 87 supports a deflector plate 89 which extends from near the edge of the knife 51 to the rear edge of a slice-receiving platter 90.

The detachable mounting of the deflector plate 89 consists of a bar 91 secured within the front wall of the enclosure 87 (as indicated in Fig. XII), which bar is provided with keyhole-shaped openings 92 to receive buttons 93 that are riveted to the deflector plate 89 and extend, through slots 94 in the enclosure wall, into engagement with the keyhole-shaped openings 92. Adjustment of the bar 91 to properly position the deflector plate is provided for by making holes in the enclosure wall, through which fastening screws 95 extend, larger than the shanks of the fastening screws.

The slice-receiving platter 90 is removably attached to the base portion 24 of the cast frame 23 by means of clips 96 and thumbscrews 97 (see Fig. V).

In order to prevent ingress of juices and particles of meat and other commodities into the interior of the enclosure 87, the opening under the circular knife 51 is closed by a sheet 98 which is held in place by screws 99 threaded into the enclosure 87.

It will be evident that the commodity tray 38, the gauge plate 69, the deflector plate 89, the slice-receiving platter 90 and the knife guard 56 all are easily removable and replaceable so that parts touched by meat or other foods during slicing operations can be easily sterilized.

Cracks and crevices have been avoided to the greatest practical extent, and the machine has been designed with smooth contours to facilitate cleaning.

A switch 100, for stopping and starting the motor 41, is mounted on the left wall of the enclosure 87 where it can be easily reached by the operator. When the motor is started, it acts through the worm 43 and worm wheel 48 to rotate the knife 51 at high speed, so that the edge of the knife slices swiftly through any commodity that is moved over it.

With the knife in motion, the operator grasps the handle 40 and moves the commodity tray 38 to and fro over the knife. Each time that the operator pulls the commodity tray forward the commodity in the tray slides downwardly along the V shaped bottom of the tray into engage-

ment with the face of the gauge plate, and each time that the operator pushes the commodity tray over the knife edge the swiftly turning edge cuts a slice from the lower end of the commodity, and the slice is guided by the deflector plate onto the slice-receiving platter.

The stationary shaft 26 is lubricated by oil which is carried to the shaft by a wick 101 from a pocket 102 in the carriage 27 (see Fig. II), so that the reciprocating movement of the carriage on the stationary shaft takes place with little friction, and its movement is noiseless. In order to cushion any shock and avoid any noise of impact that might be caused by striking the carriage against the end of the housing portion 25, heavy soft rubber washers 103 are placed on the shaft 26 adjacent its ends.

Located in the upper part of the enclosure 87, and concealing a sharpening device (not shown) that is mounted on a stand 111 and may be brought into position to sharpen the knife 51, is a hatch, which normally is closed by a hatch cover 104 (Fig. XI), the hatch cover being normally held in closed position by a spring catch 105 having a hook which engages an eye in a lug 106 welded or brazed to the inner side of the hatch cover. The hook may be disengaged from the eye by means of a push button 107, which engages the spring catch 105 and extends to the exterior of the enclosure.

The end wall of the hatch cover 104 fits into a cut-out section of the knife guard 56 (see Figs. III and IV) and is shaped to conform to the contour of the knife guard 56. The hatch cover forms a portion of the knife guard and, when it is swung away, exposes a short sector of the knife edge. When the hatch cover 104 is closed, the knife guard is locked into place and the guard cannot be lifted off the clips 58 for removal until the hatch cover is swung out of the way.

The embodiment of the invention herein shown and described is to be regarded as illustrative only, and it is to be understood that the invention is susceptible to variation, modification and change within the spirit and scope of the subjoined claim.

Having described my invention, I claim:

In a slicing machine having a revoluble circular knife blade the edge of which is inclined from the vertical, a frame having a housing portion extending fore and aft along the lower portion of said knife blade, a stationary shaft extending fore and aft within said housing portion, a pair of stationary parallel rails lying below said stationary shaft, a carriage slidably mounted on said stationary shaft and having a guiding roll located between said pair of stationary parallel rails, said carriage having a part extending exteriorly of said housing portion, a commodity tray having a depending bracket detachably secured to the part of said carriage extending exteriorly of said housing portion, a knife guard overlying said knife blade and being cut away to expose the forward portion of said knife blade, the top of said housing portion being shaped to form a smooth ledge lying along the lower portion of said circular knife blade and adapted to support and guide commodities for sliding movement therealong past the exposed forward portion of said knife independently of said commodity tray.

GEORGE R. WOOD.
